UNITED STATES PATENT OFFICE.

PETER SCHNEIDER, OF BROOKLYN, E. D., NEW YORK, ASSIGNOR OF ONE-HALF TO JAMES RORKE, OF SAME PLACE.

COMBINED GLOBE AND CHIMNEY FOR LAMPS.

SPECIFICATION forming part of Letters Patent No. 241,730, dated May 17, 1881.

Application filed September 2, 1879.

To all whom it may concern:

Be it known that I, PETER SCHNEIDER, of Brooklyn, Eastern District, in the county of Kings and State of New York, have invented 5 a new and Improved Combination Globe and Chimney for Lamps, of which the following is a specification.

My invention relates to improvements in that class of non-reversible combination globes 10 and chimneys for lamps and other similar purposes, wherein the top or chimney portion is adapted to serve as a shade; and the object thereof is to connect the shade and globe together, so that the light which passes through 15 the globe will not be intercepted by the shade, but will pass out into the surrounding space; also, to make the connection in such a manner that the contraction and expansion at the base of the shade and the top of the globe will be 20 about equal, and fracture thereby avoided.

The invention consists, first, of a transparent globe surmounted by a bell-shaped opaque or semi-opaque shade which has its top contracted to form a chimney, and the base joined 25 to the globe, but not extended beyond the same, and in connecting the top of the globe and the shade together so that the lateral extension of the top opening of the globe is beyond or outside of the base of the globe, and 30 at the same time the horizontal dimensions of the shade do not exceed the globe.

In the accompanying drawings, Figure 1 represents a side elevation of my improved globe and chimney; and Fig. 2 represents a 35 vertical section of the same, taken on line $x-x$ of Fig. 1.

Referring to the drawings, A represents the globe, the base a of which may be adapted to the burner with which the globe is used. 40 The convex sides b of the globe and its top d extend laterally beyond the base a , whereby the opening e in the top of the globe is considerably larger than the base a .

B represents the shade, which is contracted 45 at the top portion, D, to form a throat, f , of less area laterally than the opening g in the base a , so as to serve as a chimney. The base of shade B is formed of a flange, h , and this flange is connected with the rim l projecting 50 outward from the top d of the globe, the shade, flange, rim, and globe all being in one piece. The base-flange h has about the same horizontal dimensions as the globe at its widest portion, (indicated by the horizontal dotted line

connecting the sides b), so that the extreme 55 convex portions b of the globe fall in the same perpendicular plane as the base-flange h , as indicated by the vertical dotted lines. The object of this arrangement is twofold.

First, the sides of the globe and the base of 60 the shade being about equally distant from the line of draft through the chimney f , they contract and expand about equally, and thereby fracture at the connection of the shade and globe is avoided. To attain this object the base 65 of the shade should not extend horizontally beyond the sides of the globe at their widest part.

Second, the rays of light passing through 70 the globe, as indicated by the dotted lines, are not intercepted by the shade, but are thrown out into the surrounding space, while the rays which pass upward are intercepted and thrown down. By this arrangement the circle of illumination is not contracted by the shade, and 75 at the same time the shade intercepts and throws down the rays of light which would otherwise be thrown upward.

The top d of the globe being extended 80 horizontally beyond the base a , the overheating of the connection between the globe and shade is prevented, and as the base-flange h is not extended beyond the globe, it will be seen that the top d and rim l are at such a distance from the line of draft that they are about 85 equally exposed to the heat when the lamp is lighted, and to about the same rate of cooling.

I claim—

As an improvement in non-reversible combination globes and chimneys formed in one 90 piece, the globe A, having its top d extended laterally beyond the base of the globe, and provided with the outwardly-projecting horizontal rim l , in combination with the bell-shaped shade B, contracted to form a chimney, f , and 95 having its base provided with a flange, h , connected to the rim l about in line with the sides b of the globe, and so as not to extend outside of said sides laterally, whereby the connection between the globe and shade is extended laterally beyond the base of the globe 100 and out of the line of draft through the chimney, substantially as herein shown and described.

PETER SCHNEIDER.
